HOT LATHER DISPENSER

Douglas A. Long, Wilton, and Frederick A. Burke, River-side, Conn., assignors to Clairol Incorporated, New York, N.Y.

Filed Dec. 24, 1974, Ser. No. 536,066

Term of patent 14 years

Int. Cl. D9—01

U.S. Cl. D6—95

T1Q.6.

FIG. 1 is a perspective view of a hot lather dispenser showing our new design;

FIG. 2 is a side elevational view;

FIG. 3 is a bottom plan view;

FIG. 4 is a rear elevational view;

FIG. 5 is a front elevational view; and

FIG. 6 is an exploded perspective view.

We claim:

The ornamental design for a hot lather dispenser, as shown and described.
